CONTAINER FOR CARDS

Charles W. Beck, Toledo, Ohio

Application March 8, 1935, Serial No. 10,058

8 Claims. (Cl. 206—74)

This invention relates to card containers, cigarette holders, containers for prescription blanks for doctors, containers for memo blanks and the like.

5 The invention has for its particular object, a hinge mechanism for containers in which the entire hinge mechanism and locking means is placed on the inside of the container, to the end that no part of either the hinge or the locking mechanism is exposed on the outside of the container.

The hinge mechanism and locking means further embody means whereby the cover for the container may be moved horizontally to first un-

10 lock the means for fastening the cover and pivotal means whereby the cover may be rotated to open it, without having any part of the mechanism perforate the case and permit dust and dirt to enter the container.

15 20 The further purpose of the invention is to make a container of plastic material in various colors which is dustproof and pleasing in its appearance.

25 Fig. 1 is a plan view of the container in which the inside parts of the container are illustrated by dotted lines.

Fig. 2 is an end view of Fig. 1.

Fig. 3 is a cross section of Fig. 1 along lines A—A and B—B.

30 Fig. 4 is a plan view illustrating a modification of some of the features of the invention embodied in Fig. 1 with the body member in one unit and made of metal.

35 Fig. 5 is a side view of the container illustrated in Fig. 4.

Fig. 6 is an end view of the container shown in Fig. 4.

Fig. 7 is an enlarged section of the container showing the container closed with the hinge mechanism in section along lines A—A of Fig. 1.

40 Fig. 8 is a fragmentary section of the side walls 1^c in section along lines C—C of Fig. 1.

Fig. 9 is a plan view of the container in modified form.

45 Fig. 10 is a side view of the container of Fig. 9.

Fig. 11 is an enlarged cross section along lines A—A of Fig. 9.

50 Fig. 12 is an enlarged plan view of the lefthand end of the container shown in Fig. 9 illustrating the hinge mechanism in dotted lines.

Fig. 13 is an enlarged cross section along lines B—B of Fig. 9 illustrating the locking device of the container.

Fig. 14 is an enlarged cross section of the container and hinge mechanism along lines C—C of Fig. 11.

5 Referring to the drawings, the container proper, consists of the body member 1 and the cover member 2, which two members form the enclosure of all sides of the container, both of which members are preferably molded of plastic compound, while the hinge and closure mechanism is made of metal, except in the modifications shown in Figs. 9 to 14 inclusive, the catch for holding the cover of the container in closed position is formed also of plastic material molded integral with the cover and the body member.

10 The body member of the container shown in Figs. 1, 2, 3, 7, 8, 9 to 14 inclusive, is made of plastic material and is formed with a bottom 1^a, two side walls 1^c and an end wall 1^b with an open end at the right. Intermediate of the two ends of the body member and forming part of 15 the side walls 1^c are thickened wall sections 15^b with a channel 15 and an upstanding ledge 15^a as illustrated in Fig. 8 which is along lines C—C of Fig. 1. This thickened wall section 15^b terminates to the left of lines C—C as shown by 20 dotted lines in Fig. 1. The ledge 15^a terminates in the proximity of the locking pins 7, Fig. 1. The cover 2 is provided with an end wall 2^c which in connection with the sides and end wall of the body member 1 form the closed cavity of the 25 container. The cover 2 is further provided with side rails 16 which extend the entire length of the cover and when the cover is closed register in the channel 15 of the body member as illustrated in Fig. 2. The side rails 16 of the cover 30 are made deeper at the left end of the cover as shown by 16^a Figs. 3 and 7. This part of the side rails of the cover are drilled with two holes (one on each side) into which shaft 5 is projected when the hinge mechanism has been 35 assembled.

40 The hinge mechanism consists of main body member 3 which has a flat horizontal portion illustrated between the body member 1 and rivet 8, Figs. 3 and 7. This hinge member 3 is further 45 provided with two curled parts to receive the shaft 6. These curled parts are located at the extreme sides of the body member 3 and are formed of lips of metal lanced from part 3 for a portion of the distance, so as to form the support for the shaft 6 and the two link members 4 intermediate of the base of the hinge member 3 and the cover, as shown in Figs. 3 and 7. The flat portion of the hinge member 3 is also provided with two holes for the rivets 8 which latter 50

55

are molded into the body member 1 as shown by Figs. 1, 3 and 7. The inclined part of 3 has riveted at its upper end and in the middle thereof a spring 9 by two rivets 10. This spring holds the cards in position in the container. Part 11 is molded into the cover as shown at 18 and consists of a spring wire bent into U shape so that when the base of the U shaped wire is molded into the cover the two ends projecting are at right angles to 18. Two small soft rubber tubes 12 are telescoped over the ends of the wire 11 which when the cover of the container is closed bear downward as shown in dotted lines Fig. 3. The same is true of flat spring 9 and is also shown 15 in that position Fig. 3.

Links 4 are provided with slots 4^a to permit the shaft 5 to move forwards and backwards in the slots in links 4. The shaft 5 is anchored in holes in the side rails 16^a of the cover 2 so that when 20 the latter is moved forwards or backwards the shaft 5 is moved with it to the extent permitted by the slots in links 4 while the hinge member and the parts attached to it are held stationary in the case 1 by rivets 8. This horizontal motion back and forth opens and engages the catches or locking pins 7 so that the cover may be raised and then closed and locked. To aid the movement of the cover back and forth, panels 19 and 20 are roughened or stippled to assist adhesion between the thumb or fingers to push the cover forward or backwards.

At the right of Fig. 3 the container is shown in section along lines B—B of Fig. 1. This illustrates the locking pins 7 in closed position. 35 The locking pins are made of round rod, bent at right angles and flattened on the upper half and are inserted into the container pointing to the right and in the cover pointing to the left so that the motion of the cover to the right and 40 left unlocks and locks these catches. Those on the cover are inserted into the rails 16 of the cover and those on the container into the thickened wall section 15^b.

The assembly of the container illustrated in 45 Figs. 1, 2, 3, 7 and 8, is begun with the hinge mechanism by inserting shaft 6 into position after riveting spring 9 thereto, then placing links 4 on the ends of shaft 6 and peening over the ends of the shaft 6 so as to hold the links 50 thereon; now the entire hinge assembly, comprising the body member 3, the spring 9, the shaft 6 and the two links 4, is placed upside down on the inside of the cover between the two rails 16^a and shaft 5 is first inserted into one of the 55 holes in rail 16^a and forced through the slots in links 4 to the other side rail 16^a and then further forced through the side rail, so as to register evenly with the outside of the side rails of the cover. This prevents the shaft 5 from 60 being displaced when in position on the container. The lockpins 7 are assembled by a press fit into holes molded in the side rails of the cover and the thickened wall section 15^b of the container. The cover end with the enlarged side 65 rails 16^a is then placed between the side walls of the container 1 and the flat part of the metal hinge with the two holes are forced into registry with the rivets 8 of the container, after which 70 the cover is forced forward and a punch is placed between the inside of the endwall 1^b and the cover, with which punch the rivets are turned over to permanently hold the cover and the hinge mechanism in operative position on body member 1.

To operate the container, the cover is pushed forward to disengage the locking pins 7, the cover is then raised, after which the spring 9 is raised with the fingers and a suitable quantity of cards placed in the container and the cards are pushed backwards against the inclined part of the hinge member so as to taper the cards as shown at 14 Fig. 5. The spring 9 is then permitted to rest on top of the cards. As the cover is brought down and the cover closed and pushed back to engage the locking pins 7 the ends 12 of the U spring 11 will rest on top of the cards under tension and when the cover is pushed forward to open the container and the cover rotated on the hinge into right angled position with the body member of 15 the container, the top card will be brought forward by 12 to separate it from the balance of the cards in the container for easy removal.

The purpose of the inclined part of the hinge member 3 in addition to supporting the spring 9, is to taper the cards when pushed against it, in the shape as shown in Fig. 5 at 14, so that the top card always projects beyond the other cards below it for easy removal.

The panel 21 on the outside of the cover 2 is 25 for the name of the owner or for advertising matter.

Figs. 4, 5 and 6 illustrate the invention in part only, showing a metal case 1 with the incline at the left against which the cards are pushed when 30 inserted in the case, which latter is made of one part and open at the right, with the cards showing tapering from the top down, so that the top card is always forward for easy removal. The metal case shown has no cover, but embodies the 35 flat spring 9 for which an opening is provided in the top of the case, through which the spring will press on the cards until they are all used as shown by dotted lines 9^a of the spring in Fig. 5. The spring is riveted to the case by rivets 10. 40 The metal case may be provided with ribs 13 for the purpose of strengthening and to act as a stop for a cover made of metal to telescope the end of the case 1 and cover the cards projecting therefrom.

Figs. 9, 10, 11, 12, 13 and 14 show a slightly different construction of the hinge arrangement and the closure catches. In this construction the body member 1 has no thickened portion of the side walls 1^c and the cover 2 is not provided with 50 side rails 16; however, the container body is provided with projections 1^a on the inside of the sidewalls 1^c to prevent the cover 2 from being pressed down too far, also to keep the cards in place and to indicate the height to which the 55 cards may be placed in the container. 2^a represents a metal strip molded into the end of the cover 2 as shown in section of lines A—A Fig. 11 and dotted lines Fig. 12, also in cross section along lines C—C of Fig. 11 and Fig. 14. This 60 metal strip 2^a has slots arranged in right angled extensions of the strip indicated by 2^b Figs. 11, 12 and 14. The hinge member 3 is shaped with a flat part which is riveted to the body member of the container the same as the hinge member of 65 Figs. 1, 2, 3 and 7, but with the construction shown in Figs. 11, 12 and 14 no links 4 are necessary, because it is practical to make the slots in the metal strip 2^a as indicated by 2^b before this strip is molded into the cover, while it is not practical 70 to mold the slots into the side rails 16^a shown in Figs. 1, 2, 3 and 7. The hinge member 3 also has an inclined part to which the flat spring 9 is riveted by rivets 10, but the support for shaft 5 is provided in a right angled extension of the 75

flat part of the hinge member 3 indicated by 3^b Figs. 11 and 14. Instead of needing two shafts or pivotal points shown in Figs. 1, 2, 3 and 7 only one shaft is needed in the construction of Figs. 9 to 14 inclusive because the function of the link is dispensed with by the slot in parts 2^b and the cutting away the top of the right angled extensions 3^b as illustrated in Fig. 11 showing a side elevation of the extension 3^b forming a radius of the shaft 5 to permit the elevation of cover 2 to a position at right angles to the body of the container when the cover is opened for the removal of cards. The assembly of the cover and hinge mechanism may be made in the same manner as described previously for Figs. 1, 2, 3 and 7, leaving the links out of consideration and cutting the lengths of shaft 5 so that the ends of the shaft register with the inside of the side walls 1^c when in position, or providing the holes in the side walls, indicated by 5^a and 5^b and making the shaft long enough to extend into the holes indicated and inserting the shaft after the hinge member 3 has been riveted into the body member 1 with rivets 8 and then placing the cover in position on the container and inserting the shaft 5 from the outside of the sidewall into the hole 5^a and pressing it into position until it registers with the blind hole 5^b on the inner side of the side wall of the body member 1.

Fig. 13 illustrates the righthand end of the container in section along lines B—B of Fig. 9. This sectional view illustrates the cover 2 with the end wall 2^c, the body member 1 with the raised lip 7 and a corresponding cavity 7^a on the inner side of end wall 2^c of the cover. The view of Figs. 11 and 13 are with the cover 2 pushed forward and the locking means disengaged and in position to raise the cover for removal of cards.

I claim:

1. A combination hinge and closure mechanism for a container, composed of a body member and a cover member, said hinge and closure mechanism comprising a slotted member, a shaft supported by the cover member of the container and passing through the slot in said slotted member for sliding movement therein, a main hinge member provided with supports for a pivot for said slotted member and cooperating means on the container members for engaging and disengaging the two container members by a sliding movement of the cover member, and a second shaft supported by the main hinge member for providing for rotation of the cover member.

2. A container of the class described, comprising two separate body members with a cavity between them, a hinge mechanism located in said cavity to hold the two body members in operative relation, said hinge mechanism providing for two separate movements of one of the body members to open and close the container, locking means on the inside of the container and independent of said hinge mechanism and means external of said body members for providing for

movement of one in relation to the other to open and close the container.

3. A container for cards comprising two body members and a hinge and closure mechanism, said hinge mechanism being provided with a bevel, a spring for holding the cards in position and means embodied in the body members and cooperating with the hinge mechanism for providing for sliding movement of one of the members to unlatch and latch the container. 10

4. A hinge mechanism for a container for cards, embodying rotary and sliding members and comprising a main hinge member with supports for said rotary and sliding members, a horizontal support on said main hinge member 15 fastened to the container and a bevel part for aligning the cards in bevel position and for holding the top card in the container forward of the remaining cards.

5. A card case embodying a body member and 20 a cover member, the two members when assembled forming a cavity for receiving cards between them, means located entirely within the cavity for attaching the cover member to the body member in operative relation, means for 25 holding the cards in the card case in fixed position, means also located on the inside of said two members for holding the body member and cover member in closed position and further means on the cover member of the card case for 30 moving the top card when the card case is opened.

6. A case including a pair of cooperating members, means to hinge the members to provide for movement of one thereof to be swung and to slide 35 relative to the other, and means independent of the hinging means to latch the members against swinging upon sliding movement of one of the members toward the hinging means and upon sliding movement of the said one member away 40 from the hinging means to thereby allow the said one member to be swung to open position.

7. A card case comprising a pair of members, means for hingedly relating the members and for providing for relative sliding movement 45 therebetween, means for latching the members against hinging, upon relative sliding movement therebetween when in closed position, and means cooperating with one of the members to slide the cards forwardly so as to partially eject same 50 from the case when the latter is opened.

8. A combination unit hinge mechanism for a container composed of two body members, said hinge mechanism comprising a main supporting member connected to one of the container members and provided with supports having pivots, members with slots supported by said pivots, a shaft operating in the slots of the slotted members and engaging the other container member to secure the said container member in operative 55 relation and means for fastening the main supporting member of the hinge mechanism to the first named container member.

CHARLES W. BECK.
